US011913329B1

(12) **United States Patent**
Zeghlache et al.

(10) **Patent No.:** US 11,913,329 B1
(45) **Date of Patent:** Feb. 27, 2024

(54) **UNTETHERED LOGGING DEVICES AND RELATED METHODS OF LOGGING A WELLBORE**

(71) Applicant: **Saudi Arabian Oil Company**, Dhahran (SA)

(72) Inventors: **Mohamed Larbi Zeghlache**, Dhahran (SA); **Huseyin Rahmi Seren**, Houston, TX (US)

(73) Assignee: **SAUDI ARABIAN OIL COMPANY**, Dhahran (SA)

(*) Notice: Subject to any disclaimer, the term of this patent is extended or adjusted under 35 U.S.C. 154(b) by 0 days.

(57) **ABSTRACT**

An untethered device includes a housing, a magnetic actuator that is coupled to the housing, and a buoyancy device. The buoyancy device includes an attachment plate that is securable to the magnetic actuator, a degradable ballast weight that is coupled to the attachment plate, and a buoyancy-enhancing feature that is positioned adjacent to the attachment plate.

UNTETHERED LOGGING DEVICES AND RELATED METHODS OF LOGGING A WELLBORE

TECHNICAL FIELD

This disclosure relates to untethered devices, such as untethered logging devices that include a buoyancy device with a relatively buoyant attachment plate and a degradable ballast weight.

BACKGROUND

Untethered devices in oil and gas applications refer to untethered logging, intervention, stimulation, or other devices that are unattached to a wellbore surface and are deposited in a wellbore to descend in a downhole direction. Such an untethered device may include a release mechanism whereby an exposed ballast weight degrades or is released at a downhole depth along the wellbore to reduce a density of untethered device for allowing the untethered device to float back upward to the surface. The release mechanism may include an attachment plate that, owing to its weight, settles permanently in a bottomhole region of the wellbore. An accumulation of such attachment plates at the bottomhole region (e.g., especially because the attachment plates do not erode quickly) can lead to wellbore cluttering, which is hinders various wellbore interventions and bottomhole operations. Furthermore, heat produced by the highly exothermic reaction undergone by the exposed ballast weight can permanently damage the other components of the untethered device while attached to the ballast weight.

SUMMARY

This disclosure relates to untethered logging devices that include a buoyancy device with a relatively buoyant attachment plate and a degradable ballast weight. Upon release of the buoyancy device from a remaining functional module of the untethered logging device, the functional module floats in an uphole direction towards the surface. Upon sufficient degradation of the degradable ballast weight of the buoyancy device, the attachment plate floats in the uphole direction towards the surface. The functional module of the untethered logging devices are designed to log the wellbore while flowing in both downhole and uphole directions within the wellbore.

In one aspect, an untethered device includes a housing, a magnetic actuator that is coupled to the housing, and a buoyancy device. The buoyancy device includes an attachment plate that is securable to the magnetic actuator, a degradable ballast weight that is coupled to the attachment plate, and a buoyancy-enhancing feature that is positioned adjacent to the attachment plate.

Embodiments may provide one or more of the following features.

In some embodiments, the buoyancy-enhancing feature includes a buoyant material layer.

In some embodiments, the buoyant material layer is disposed between the attachment plate and the degradable ballast weight.

In some embodiments, the buoyant material layer includes a syntactic foam.

In some embodiments, the degradable ballast weight is attached directly to the buoyant material layer.

In some embodiments, the buoyancy device is separable as an entire unit from the magnetic actuator.

2

In some embodiments, components of the buoyancy device are secured to one another via one or more mechanical fasteners.

In some embodiments, components of the buoyancy device are secured to one another via one or more adhesive substances.

In some embodiments, the buoyancy-enhancing feature includes void regions within the attachment plate.

In some embodiments, the attachment plate is attached directly to the degradable ballast weight.

In some embodiments, the degradable ballast weight is non-magnetic.

In some embodiments, the untethered device further includes one or more sensors configured to measure one or more properties within a surrounding wellbore.

In some embodiments, the untethered device is configured to continuously log the surrounding wellbore while the untethered device flows in a downhole direction and while the untethered device flows in an uphole direction.

In some embodiments, the untethered device is an untethered logging device.

In another aspect, a method of logging a wellbore includes dropping an untethered logging device in a downhole direction through the wellbore. In some embodiments, the untethered logging device includes a functional module including a magnetic actuator, an attachment plate that is equipped with a buoyancy-enhancing feature and coupled to the magnetic actuator, and a degradable ballast weight that is attached to the attachment plate. The method further includes releasing the attachment plate from the magnetic actuator to reduce a bulk density of the untethered logging device and flowing the functional module of the untethered logging device in an uphole direction through the wellbore.

Embodiments may provide one or more of the following features.

In some embodiments, the method further includes allowing the degradable ballast weight to degrade to reduce a bulk density of an assembly of the degradable ballast weight and the attachment plate and flowing the attachment plate in the uphole direction through the wellbore.

In some embodiments, the buoyancy-enhancing feature includes a buoyant material layer.

In some embodiments, the buoyant material layer includes a syntactic foam.

In some embodiments, the buoyancy-enhancing feature includes void regions within the attachment plate.

In some embodiments, the method further includes measuring one or more properties within the wellbore while the functional module flows in the downhole direction and in the uphole direction.

The details of one or more embodiments are set forth in the accompanying drawings and description. Other features, aspects, and advantages of the embodiments will become apparent from the description, drawings, and claims.

DESCRIPTION OF DRAWINGS

FIG. 1 is a diagram of example untethered logging devices within a wellbore.

FIG. 2 is a cross-sectional view of an example untethered logging device of FIG. 1, including a buoyant layer that is secured between an attachment plate and a ballast weight.

FIG. 3 is an enlarged view of a buoyancy device of the untethered logging device of FIG. 2, including the buoyant layer, attachment plate, and ballast weight of FIG. 2.

FIG. 4 is a graph of an example relationship between a thickness of the attachment plate of FIG. 2 and a holding force on the attachment plate.

FIG. 5 is a flow chart illustrating an example method of logging a wellbore using an untethered logging device of FIG. 2 or an untethered logging device of FIG. 6.

FIG. 6 is a cross-sectional view of an example untethered logging device, including a ballast weight and an attachment plate with void regions.

FIG. 7 is an enlarged view of a buoyancy device of the untethered logging device of FIG. 6, including the ballast weight and the attachment plate of FIG. 6.

FIG. 8 is an enlarged view of the attachment plate of FIG. 6.

DETAILED DESCRIPTION

FIG. 1 illustrates several states of example untethered logging devices 100 (e.g., 100a, 100b, 100c, 100d, 100e) for measuring properties (e.g., collecting data) along a wellbore 101 to log the wellbore 101. Such properties may be related to one or both of wellbore fluid 109 within the wellbore 101 or a rock formation 115 in which the wellbore 101 is formed. The untethered logging devices 100 are unattached (e.g., either directly or indirectly) to a surface 103 from which the wellbore 101 extends. The untethered logging devices 100 are deployable to the wellbore 101 to flow in a downhole direction 105 through the wellbore fluid 109 while logging the wellbore 101 (e.g., refer to 100a), to sufficiently increase their buoyancy when the untethered logging devices 100 reach a target depth 111 along the wellbore 101 (e.g., refer to 100b), and to consequently flow in an uphole direction 107 through the wellbore fluid 109 towards the surface 103 while logging the wellbore 101 (e.g., refer to 100c).

FIG. 2 illustrates a cross-sectional view of an example untethered logging device 100. The untethered logging device 100 includes a main housing 102 that contains or otherwise protects various internal components, an electromagnetic activation unit 104 disposed adjacent to the main housing 102, a buoyancy device 106 that is coupled to the electromagnetic activation unit 104, and a protective wall 108 that surrounds the buoyancy device 106 laterally. The main housing 102 has a substantially frusto-spherical shape (e.g., the shape of a partial sphere) such that the untethered logging device 100 may sometimes be referred to as a sensor ball. The electromagnetic activation unit 104 includes a magnetic actuator 110 and a substantially cylindrical wall 112 that protects the magnetic actuator 110. The main housing 102 and the electromagnetic activation unit 104 together form a functional module of the untethered logging device 100. The buoyancy device 106 is substantially disc-shaped (e.g., shaped substantially as a solid cylinder), and the protective wall 108 accordingly has a substantially cylindrical shape. The protective wall 108 is open at a downhole end 114 such that the buoyancy device 106 is exposed to the wellbore fluid 109 at all times.

The buoyancy device 106 includes an attachment plate 116, a buoyant layer 118, and a ballast weight 132. The attachment plate 116 is a metal plate that is made of one or more ferromagnetic materials, such as high-permeability, soft ferromagnetic materials (e.g., carbon steels or nickel-iron alloys). The resulting attractive force between the attachment plate 116 and the magnetic actuator 110 ensures that the attachment plate 116 remains secured to the magnetic actuator 110 until the magnetic actuator 110 is operated to release the entire buoyancy device 106 as a unit from the electromagnetic activation unit 104 of the untethered log-

ging device 100 (e.g., refer to 100b in FIG. 1) at the target depth 111 (e.g., a preprogrammed depth that is detected based on a sensor measurement). Upon release of the buoyancy device 106 from the electromagnetic activation unit 104, an overall (e.g., bulk) density of the untethered logging device 100 decreases (e.g., instantaneously) to a value that is less than that of the wellbore fluid 109. Accordingly, the untethered logging device 100 (e.g., the functional module remaining after release of the buoyancy device 106) is buoyant enough to float in the uphole direction 107 (e.g., refer to 100c in FIG. 1) to be retrieved at the surface 103. In this way, connection or disconnection of the buoyancy device 106 governs whether the untethered logging device 100 descends (e.g., sinks) in the downhole direction 105 or ascends (e.g., floats upward) in the uphole direction 107 through the wellbore fluid 109.

While the remaining functional module of untethered logging device 100 floats upward, the buoyancy device 106 continues to descend as a unit toward the bottomhole end 113 of the wellbore 101 (e.g., refer to 100d in FIG. 1). While the buoyancy device 106 remains in the wellbore 101, the ballast weight 132 gradually degrades over an extended period of time (e.g., several hours to several days). Once the ballast weight 132 degrades to the extent that the overall density of the buoyancy device 106 is less than that of the wellbore fluid 109, the buoyancy device 106 begins to float in the uphole direction 107 towards the surface 103 (refer to 100e in FIG. 1). In some examples, a minimal volume of the ballast weight 132 is still attached to the attachment plate 116 once the buoyancy device 106 reaches the surface 103. In other examples, the ballast weight 132 has degraded substantially entirely by the time the buoyancy device 106 reaches the surface 103.

In this way, a state of the ballast weight 132 (e.g., the extent to which the ballast weight 132 has degraded) governs whether the buoyancy device 106 descends in the downhole direction 105 or ascends in the uphole direction 107 through the wellbore fluid 109. For example, when the state of the ballast weight 132 is such that the bulk density of the buoyancy device 106 is greater than the density of the wellbore fluid 109, there is a positive differential in density that renders the buoyancy device 106 relatively non-buoyant, causing the buoyancy device 106 to descend through the wellbore fluid 109 in the downhole direction 105. In contrast, when the state of the ballast weight 132 is such that the overall density of the buoyancy device 106 is less than the density of the wellbore fluid 109, there is a negative differential in density that renders the buoyancy device 106 relatively buoyant, causing the buoyancy device 106 to ascend through the wellbore fluid 109 in the uphole direction 107 for retrieval at the surface 103.

Referring still to FIG. 2, the ballast weight 132 includes a solid core 134 that may be made of one or more non-magnetic materials, such as aluminum, magnesium, and a metal-polymer composite material. The ballast weight 132 also includes a coating 136 that initially surrounds an exposed exterior surface of the solid core 134 to delay or otherwise extend the degrading process of the solid core 134. A presence of the coating 136 may ensure that the untethered logging device 100 sinks to the target depth 111 before the solid core 134 can sufficiently degrade to critically reduce the overall density of the untethered logging device 100. The coating 136 may be made of one or more materials, such as a polymer (e.g., epoxy or xylan) or an oxide (e.g., alumina or silica). The coating 136 may be applied to the solid core 134 by utilizing one or more

conventional techniques, such as dip coating, spray coating, anodization, electrodeposition, or vapor deposition.

The buoyant layer 118 is positioned between the attachment plate 116 and the ballast weight 132. The buoyant layer 118 is made of one or more relatively low-density materials to lower an overall density of the buoyancy device (e.g., an effective density of the attachment plate 116). The buoyant layer 118 accordingly increases an overall buoyancy of the buoyancy device 106. For example, the effect of the buoyant layer 118 is that, once the ballast weight 132 has sufficiently degraded (e.g., by about 10% or more), the overall density of the buoyancy device 106 (e.g., an assembly of the attachment plate 116, the buoyant layer 118, and any small volume of remaining ballast weight 132) is low enough (e.g., less than that of the wellbore fluid 109) to cause the buoyancy device 106 to float in the uphole direction 107 back to the surface 103.

In some embodiments, the buoyant layer 118 is made a syntactic foam. In some embodiments, the buoyant layer 118 has a density between about 0.5 g/cm³ and 0.7 g/cm³, a hydrostatic crush pressure resistance between about 2,000 psi and about 30,000 psi, a compressive modulus between about 100,000 psi and about 900,000 psi, a glass transition point above about 150° C., and a thermal conductivity between about 0.05 W/m-K and about 0.5 W/m-K. In some embodiments, the buoyancy layer has a thickness (e.g., a vertical height) between about 0.5 cm and about 5 cm.

Referring to FIG. 3, the components of the buoyancy device 106 are secured to one another via multiple fasteners (e.g., screws, bolts, or nuts) that are resistant to a relatively high-temperature environment of the wellbore 101. For example, the buoyant layer 118 is secured to the ballast weight 132 with one or more screws 138, and the buoyant layer 118 is secured to the attachment plate 116 with one or more bolt-and-nut combinations 160. In other embodiments, the components of the buoyancy device 106 may alternatively or additionally be secured to one another via adhesives (e.g., between the attachment plate 116 and the buoyant layer 118 and between the buoyant layer 118 and the ballast weight 132). Example adhesives that may be used include super glue, polyurethane, and silicone. In either case of fasteners or adhesives, the attachment plate 116 is permanently secured to the buoyant layer 118. By carefully engineering details of the one or more fasteners (e.g., length, diameter, thread count, and size) or surface areas of any applied adhesives, attachment of the components of the buoyancy device 106 to one another may be ensured.

Advantageously, as compared to conventional logging devices with ballast-release systems, the design aspects of the buoyant layer 118 avoid multiple interventions that may otherwise need to be performed at the wellbore 101 to recover the attachment plate 116 from the bottomhole region 113 of the wellbore 101. In this manner, the buoyant layer 118 prevents clutter resulting from attachment plates 116 that may otherwise accumulate at the bottomhole end region 113. Accordingly, the buoyant layer 118 provides the untethered logging device 100 with a zero-waste feature that results in safer and cleaner well operations. Additional advantages arise from the buoyant layer 118 as well. For example, the buoyant layer 118 serves as a shock absorber for the other components of the untethered logging device 100 while the untethered logging device 100 descends through the wellbore 101. The buoyant layer 118 also serves as a thermal shield that protects the other components of the untethered logging device 100 from the highly exothermic degradation (e.g., dissolving) process gradually undergone by the ballast weight 132.

Referring again to FIG. 2, the example untethered logging device 100 further includes circuitry 120 that controls various functionalities of the untethered logging device 100. In some embodiments, the circuitry 120 includes a receiver 122, a transmitter 124, a controller 126, and one or more processors 128. The untethered logging device 100 also includes a battery 130 that powers various components of the untethered logging device 100. The magnetic actuator 110 is magnetized by the battery 130 to hold the buoyancy device 106 at the attachment plate 116 until a detected parameter triggers deactivation for release of the buoyancy device 106. Referring to FIG. 3, the magnetic actuator 110 includes a magnet 142 and two magnetic steel poles 144. The magnet 142 includes a low coercivity magnet with a coil wrapped around it and a high coercivity magnet. By applying brief current pulses to the coil, a pull force can be effected to hold the attachment plate 116 of the buoyancy device 106.

The untethered logging device 100 includes also one or more sensors 140 that are continuously powered by the battery 130 and designed to measure one or more physical, chemical, geological, or structural properties along the wellbore 101 to log the wellbore 101 continuously and in real time. Example properties include elapsed time, temperature, pressure, fluid density, fluid viscosity, fluid flow rate, magnetic field, gamma ray intensity, tool acceleration, tool rotation, and other parameters. The continuous measurements are acquired while the untethered logging device 100 both descends and ascends through the wellbore fluid 109. During the logging operation, the transmitter 124 sends data carrying the real-time measurements to one or more devices located at the surface 103 for further processing of the data.

In some embodiments, a weight of the untethered logging device 100, excluding the ballast weight 132, is in a range of about 25 g to about 500 g. In some embodiments, the ballast weight 132 weighs between about 10 g and about 300 g. Measured to the downhole end 114 of the protective wall 108, the untethered logging device 100 typically has a total height of about 5 cm to about 30 cm. The untethered logging device 100 typically has a width (e.g., determined by a diameter of the main housing 102) of about 5 cm to about 10 cm. Each of the main housing 102, the closed wall 112, and the protective wall 108 may be made of one or more materials, such as metals (e.g., steel, titanium, or nickel-chromium-based alloys), syntactic foam, thermoplastics, and carbon fiber materials.

Additionally, there are at least two other important parameters that should be considered with respect to the design of the untethered logging device 100. These parameters include a thickness of the attachment plate 116 and an effective density of an assembled combination of the attachment plate and the buoyant layer 118 (e.g., a combined layer 148). The thickness of the attachment plate 116 determines a holding force that can be exerted by a combined effect of the magnetic actuator 110, a magnetic field strength of the magnet 142, and a magnetic permeability of the ferromagnetic material from which the attachment plate 116 is made. If the attachment plate 116 is thinner than a critical thickness, then the magnetic field saturates the attachment plate 116, thereby greatly reducing its magnetic permeability. As a result, a reluctance of the attachment plate 116 increases, and an affinity that allows the magnetic field to remain inside of the attachment plate 116 is reduced. This reduced affinity causes the magnetic field to leak such that the holding force applied to the attachment 116 plate is reduced. FIG. 4 provides a graph 162 of an example relationship between a

plate thickness and a holding force that was generated using a finite element modeling simulation.

In order for the untethered logging device 100 to reach the target depth 111, the combined layer 148 should be less buoyant than the wellbore fluid 109 (e.g., having a density of about 1.0 g/cm³ for water and a density of about 0.75-0.9 cm³ for oil). For example, for the combined layer 148 to have an effective density of about 0.85 g/cm³, a steel attachment plate 116 of about 2 cm³ (e.g., having a density of about 7.85 g/cm³) would require a buoyant layer 118 of about 70 cm³ (e.g., having a density of about 0.65 g/cm³) or about 16 cm³ of trapped air.

FIG. 5 is a flow chart illustrating an example method 200 of logging a wellbore (e.g., the wellbore 101). In some embodiments, the method 200 includes a step 202 for dropping an untethered logging device (e.g., the untethered logging device 100, 300) in a downhole direction (e.g., the downhole direction 105) through the wellbore. In some embodiments, the untethered logging device includes a functional module (e.g., an assembly of the main housing 102 and the electromagnetic activation unit 104) including a magnetic actuator (e.g., the magnetic actuator 110), an attachment plate (e.g., the attachment plate 116, 316) that is equipped with a buoyancy-enhancing feature (e.g., the buoyant layer 118 or the void regions 358) and coupled to the magnetic actuator, and a degradable ballast weight (e.g., the ballast weight 132) that is attached to the attachment plate. In some embodiments, the method 200 includes a step 204 for releasing the attachment plate from the magnetic actuator to reduce a bulk density of the untethered logging device. In some embodiments, the method 200 includes a step 206 for flowing the untethered logging device in an uphole direction (e.g., the uphole direction 107) through the wellbore.

While the untethered logging device 100 has been described and illustrated with respect to certain dimensions, sizes, shapes, arrangements, materials, and methods 200, in some embodiments, an untethered logging device that is similar in construction and function to the untethered logging device 100 may include one or more different dimensions, sizes, shapes, arrangements, configurations, and materials or may be utilized according to different methods.

For example, FIG. 6 illustrates an example untethered logging device 300 that includes a different type of buoyancy device 306. The untethered logging device 300 is otherwise substantially similar in construction and function to the untethered logging device 100 and may be utilized according to the method 200. Accordingly, the untethered logging device 300 includes the main housing 102, the electromagnetic activation unit 104, the protective wall 108, the circuitry 120, the battery 130, and the one or more sensors 140. Referring to FIG. 7, the buoyancy device 306 includes a ballast weight 332 and an attachment plate 316 that is in direct contact with the ballast weight 332 along three sides. The ballast weight 332 is otherwise substantially similar in construction and function to the ballast weight 132 (e.g., including a solid core 234 and a coating 236), except that it has a different profile to accommodate a different profile of the attachment plate 316.

Referring to FIG. 8, the attachment plate 316 is a metal attachment plate that is made of the one or more ferromagnetic materials discussed above with respect to the attachment plate 116 to ensure that the attachment plate 316 remains secured to the magnetic actuator 110 until the electromagnetic unit 104 is actuated to release the buoyancy device 306. Instead of utilizing the buoyant layer 118 to increase an overall buoyancy of the attachment plate 316, the attachment plate 316 relies on its structural design. For

example, the attachment plate 316 includes an upper portion 350, a lower portion 352, columns 354 that extend between the upper and lower portions 350, 352, and an o-ring that 5 356 that substantially eliminates any outer gaps between the upper and lower portions 350, 352.

The upper and lower portions 350, 352 and the columns 354 together form multiple void regions 358 (e.g., air pockets) that reduce an overall weight (e.g., and therefore an effective density) of the attachment plate 316 as a result of material removal. The columns 354 together provide an internal truss structure that can resist relatively high crush pressures while still allowing for a relatively low density of the attachment plate 316. In some embodiments, the attachment plate 316 may be made by bring multiple pieces together or by employing additive manufacturing. A thickness and an effective density of the attachment plate 316 are critical factors for proper functioning of the attachment plate 316, as discussed above with respect to the attachment plate 116, the combined layer 148, and relationship shown in FIG. 4.

While the device 100 has been described as an untethered logging device, in some embodiments, another type of untethered device that is otherwise similar in construction and function to the device 100 can include the ballast weight-release mechanisms described above. Such devices include intervention devices, stimulation devices, and other types of untethered devices.

Other embodiments are also within the scope of the following claims.

What is claimed is:

1. An untethered device comprising:
a housing;
a magnetic actuator that is coupled to the housing; and
a buoyancy device comprising:
an attachment plate that is securable to the magnetic actuator,
wherein the attachment plate is equipped with a buoyancy-enhancing feature, and
a degradable ballast weight that is coupled to the attachment plate,
wherein the degradable ballast weight degrades to reduce a bulk density of the buoyancy device such that the attachment plate floats towards a surface.
2. The untethered device of claim 1, wherein the buoyancy-enhancing feature comprises a buoyant material layer.
3. The untethered device of claim 2, wherein the buoyant material layer is disposed between the attachment plate and the degradable ballast weight.
4. The untethered device of claim 2, wherein the buoyant material layer comprises a syntactic foam.
5. The untethered device of claim 2, wherein the degradable ballast weight is attached directly to the buoyant material layer.
6. The untethered device of claim 5, wherein the buoyancy device is separable as an entire unit from the magnetic actuator.
7. The untethered device of claim 1, wherein components of the buoyancy device are secured to one another via one or more mechanical fasteners.
8. The untethered device of claim 1, wherein components of the buoyancy device are secured to one another via one or more adhesive substances.
9. The untethered device of claim 1, wherein the buoyancy-enhancing feature comprises void regions within the attachment plate.

10. The untethered device of claim 9, wherein the attachment plate is attached directly to the degradable ballast weight.

11. The untethered device of claim 1, wherein the degradable ballast weight is non-magnetic.

12. The untethered device of claim 1, further comprising one or more sensors configured to measure one or more properties within a surrounding wellbore.

13. The untethered device of claim 1, wherein the untethered device is configured to continuously log a surrounding wellbore while the untethered device flows in a downhole direction and while the untethered device flows in an uphole direction.

14. The untethered device of claim 1, wherein the untethered device comprises an untethered logging device.

15. A method of logging a wellbore, the method comprising:

dropping an untethered logging device in a downhole direction through the wellbore, the untethered logging device comprising:

a functional module comprising a magnetic actuator, an attachment plate that is equipped with a buoyancy-enhancing feature and coupled to the magnetic actuator, and

a degradable ballast weight that is attached to the attachment plate; releasing the attachment plate from the magnetic actuator to reduce a bulk density of the untethered logging device;

flowing the functional module of the untethered logging device in an uphole direction through the wellbore; allowing the degradable ballast weight to degrade to reduce a bulk density of an assembly of the degradable ballast weight and the attachment plate; and flowing the attachment plate in the uphole direction through the wellbore.

16. The method of claim 15, wherein the buoyancy-enhancing feature comprises a buoyant material layer.

17. The method of claim 16, wherein the buoyant material layer comprises a syntactic foam.

18. The method of claim 15, wherein the buoyancy-enhancing feature comprises void regions within the attachment plate.

19. The method of claim 15, further comprising measuring one or more properties within the wellbore while the functional module flows in the downhole direction and in the uphole direction.
